UNITED STATES PATENT OFFICE

WALTER GEORGE CHARLEY, OF PUNTA SAN JUAN, CUBA

CIGARETTE AND SIMILAR ARTICLE

Application filed June 11, 1930, Serial No. 460,524, and in Cuba March 29, 1930.

This invention refers to cigarettes and similar articles, such as cigars, and has for its main object to provide an improvement in the manufacture of such articles whereby there are combined as a unit, the article and a determined igniting matter to act by friction, fitted at one end thereof, thus offering the advantage that the smoker will not be compelled to provide himself with an additional box of matches, as each cigarette will bear attached thereto the necessary lighting agent.

Another important advantage of the invention consists in that the article will also be provided with means whereby upon finishing smoking, the smoker will be able to remove the ignited end of the cigarette or cigar, which will be almost immediately extinguished as the bunch of combustible matter attached thereto will be insignificant, and the peril of fires and other dangerous accidents reduced, which often occurs in the use of matches independent from the cigarettes or cigars as well as upon throwing away the butts thereof, which remain burning for sometimes thereafter, thus transmitting fire to the surfaces with which contact is had.

A further advantage of the invention is that means are provided whereby the burnt ashes of the article are retained until such time as the smoker desires to discard same, thereby preventing the soiling of clothing, furniture or other articles, as frequently happens with cigarettes of the known type.

Further objects and advantages derived from this invention will be found in the course of this descriptive specification, especially by those persons skillful in the art to which the invention pertains, and with the aid of the figures in the attached drawings, wherein the same reference characters designate the same parts on the different views.

On the drawings:

Figure 1 is a side elevation of a cigarette provided with the improvements object of the present invention.

Figure 2 is a vertical longitudinal section.

Figure 3 illustrates a longitudinal section of a cigarette fitted to insert through same the extinguishing element or means.

Figure 4 is a side elevation, in detail, of the lighting and extinguishing agent.

Figure 5 is a detail view of a modified embodiment of the lighting and extinguishing agent.

Figure 6 illustrates a longitudinal section of a cigarette provided with the improvements object of this invention, in the act of being smoked.

Figure 7 is a similar section illustrating the step in which the lighted end is disjoined from the body of the cigarette.

Figure 8 is a similar section, but illustrating a cigarette where an extinguishing agent for the combustible portion without the ash retaining means is used.

Figure 9 illustrates, in a similar section to Fig. 8, the step of disjoining the burning end of the cigarette.

Figure 10 is another modified embodiment of the lighting, ash retaining and extinguishing agents.

Figure 11 shows a side elevation, partly broken, of the agent referred to in Fig. 10, provided with the wrapper.

Figure 12 is a sectional longitudinal view of a cigarette provided with a longitudinal perforation or chute to fit the agent shown in Fig. 11.

Figure 13 is a sectional longitudinal view of a cigarette equipped with the agent shown in Figs. 10 and 11.

Figure 14 is a sectional view of a cigarette provided with the ash retaining feature only, and

Figure 15 is a sectional view of a cigarette without the igniting head, being provided with the ash retaining and extinguishing means only.

Referring to the Figs. 1, 2, 3, 4, 6, 7, 8 and 9, inclusive, 1 designates the main body of the cigarette in which, all along its axial longitudinal center line there is a tubular chute or perforation through which there is fitted a thin pipe 2, preferably of paper, the open ends of which have outlets on each end of the cigarette body, which is clearly shown on Fig. 3. Through this pipe there is inserted a stem or rod 3 detailed on Figure 4, the head of which is made of phosphorus or other

55

100

inflammable material by friction, this head protruding and slightly separated from the front end of the cigarette body 1, as indicated on Figs. 1 and 2, and the stem or rod 3 protruding still further out on the rear end of the cigarette, as shown in Figures 1, 2, 6 and 8.

The stem or rod 3 will be made of a suitable material, for instance of an insipid non-combustible material, substantially non-conductor of heat such as glass or asbestos; or of combustible material such as paper, but it must be essential that the said material does not change or alter the taste of the cigarette or cigar objectionably.

This cigarette may be lighted by frictioning the inflammable head 4 on a rough or suitably prepared surface as if it were a match, to which end, the package of cigarettes 20 may be provided with a surface of the kind on any of its sides, the stem or rod 3 contributing to give a certain stiffness to the cigarette so as to prevent its bending or becoming damaged on the slight effort made when frictioning the head 4 to obtain light.

Upon smoking a cigarette thus manufactured, the ashes 5 will be held around the stem or rod 3, with a certain coherence, (should the stem or rod 3 have been made 30 of a non-combustible material, or even if it were of a combustible nature, it may be of such nature as to retain some stiffness even after combustion) until discard of the ashes is desired all as illustrated in Fig. 6. If this 35 ash retaining feature is not desired, the stem or rod 3 may be made of a combustible material, which would easily turn into ashes, these would keep disjoining, there being only retained the lighted end 6, attached to the 40 cigarette body 1.

Be it one case or the other, in order to extinguish the cigarette it will suffice to push the stem or rod 3 gently forward, so as to obtain removal of the lighted end 6 from the 45 cigarette body 1, as illustrated in Figures 7 and 9 of the drawings, the said lighted end thus being separated and extinguished almost immediately. Were it the case that upon manufacturing the articles, the pipe 2 became adhered to the stem 3, both parts 50 would be pushed forward in the said operation or would take the position approximately shown in Fig. 7 of the drawings.

The cigarette may be manufactured by 55 convenient mechanical devices, according to the art.

Figure 5 of the drawings illustrates a modified form of the lighting and extinguishing agent.

50 I believe it very convenient, instead of using the inflammable head 4 referred to in the foregoing description, to employ one comprising a portion made of friction-inflammable material 7 and a little mass 8 of a combustible material, to wit: paper or saw-dust,

with a suitable binding agent. This offers the advantage that the flame or the inflammable material is practically instantaneous and with the addition of the combustible material it is maintained burning for a longer time. As only sufficient friction inflammable material is required to ignite the combustible material, with which it is in intimate contact, the quantity of objectionable fumes from the ignition of the former is reduced.

The stem or rod 9 may be of glass or other suitable material with a view to obtain that the ashes may be retained with a certain coherence about the same, while the cigarette or cigar is being smoked or until such time as the smoker may desire to discard same.

The stem or rod 9 is made of glass or of any suitable material, non-heat conducting and non-combustible, and when not of a rough nature, is wrapped, adhesively, in a wrapper made of paper or of a suitable material 10, as illustrated in Figure 5, and is adapted through a conduit or perforation 11 made throughout the axial longitudinal line of the cigarette, as shown in Figure 12, for retention of the ashes, and the operation of the extinguishing feature being similar to that previously mentioned.

In Figures 10 and 11, a further modified form of the lighting, extinguishing and ash retaining agent is shown, by having a stem 13 consist of a thin wire or similar material wound in a spiral form, and provided with the so-called head made of the inflammable material 7 and the combustible material 8.

The stem or rod is wrapped with paper or other suitable material 14 and is inserted approximately through the axial longitudinal line of the cigarette, the spiral form of the wire providing an air or draft chamber

105 along its center, which insures simultaneous combustion of the wrapper and the tobacco which surrounds it. This is necessary in order that the extinguishing feature shall function satisfactorily. The spiral may be of iron or other metal (in addition to other suitable materials) as the paper wrapper effectively prevents the spiral from conducting heat to the lips or tongue of the smoker.

This spiral stem with its wrapper may project from either or both ends of the cigarette. It will be noticed that the igniting head of this stem would sufficiently project from the end of the cigarette to prevent same from being tainted with the fumes on the ignition

110 of the match head, while the paper wrapper is sufficiently combustible to burn down to the end of the cigarette, and thereby cause its lighting. It will be apparent that all the

115 features of this invention may be incorporated in the cigarette, but if desired any one, singly, may be used, without detracting from its usefulness.

Obviously, within the substantial idea above described, many changes and/or im-

provements could be effected without deviating from the spirit of the present invention, so I am not limited to the foregoing description, but desire that the Letters Patent protect all embraced within the scope of the following claims.

I claim:

1. In cigarettes and similar articles, the arrangement of a longitudinal axial chute through the body of the cigarette outletting on the ends thereof; a thin pipe inserted through said chute, and a stem of any suitable material inserted through the thin tube, one of the ends of the stem protruding from the forward end of the article, slightly spaced therefrom, and being made of a friction-inflammable material, and its opposite end protruding from the rear end of the cigarette.
2. In cigarettes and similar articles, the arrangement through the body of the cigarette of a stem wrapped adhesively with paper, the head of the stem being formed so as to protrude from the front end of the cigarette, and partially made of a friction-inflammable substance and partially of a combustible material.
3. In cigarettes and similar articles, the arrangement of a longitudinal axial chute through the body of the cigarette, and outletting on the ends thereof, a spiral stem wrapped in a tubular casing made of non-heat-conducting material inserted through the chute and protruding from one end of the cigarette.
4. In cigarettes and similar articles, the arrangement of a longitudinal axial chute through the body of the cigarette, and outletting on the ends thereof; a spiral stem wrapped in a tubular casing made of non-heat conducting material inserted through the chute, protruding from its ends, the front end of the stem being formed by a head made partially of a friction inflammable substance and partially of a combustible material.
5. In cigarettes and similar articles, the arrangement of a longitudinal axial chute through the body of the cigarette, and outletting on the ends thereof; a spiral stem wrapped in a tubular casing made of non-heat-conducting material inserted through the chute, protruding from its ends, the front end of the stem being formed by a head made partially of a friction inflammable substance and partially of a combustible material, said head being slightly spaced from the end of the cigarette.

In testimony whereof I affix my signature.
WALTER GEORGE CHARLEY.
